D12-9.

OR D 7,150 EX

DESIGN.

F. D. KENNEDY.

Sleighs.

No. 7,150.

Patented Feb. 3, 1874.

UNITED STATES PATENT OFFICE.

FRANCIS D. KENNEDY, OF ALBANY, NEW YORK.

DESIGN FOR SLEIGHS.

Specification forming part of Design No. 7,150, dated February 3, 1874; application filed November 19, 1873.
[Term of Patent 7 years.]

To all whom it may concern:

Be it known that I, FRANCIS D. KENNEDY, of the city of Albany, State of New York, have invented a Design for a "Brett" Sleigh, of which the following is a specification:

The nature of my design is fully represented in the accompanying engraved illustration, to which reference is made.

A represents the body of the sleigh, carried by the runners B and its knees C and usual beams, all of which are made permanent with the body. The body is made with an upper line, a, extending from the dickey-seat D with an easy sweep to the front of the back seat E. From the dickey-seat, in front, the front pillar-block is made with a slightly-curved line, b, terminating at the base of the toe-board F. The toe-board is slightly inclined upward in front and supported by brackets c. The lower line of the body is made with an easy-curved line, d, commencing at the front of the toe-board, and, running back, terminates at the back of the body at x, as shown. A second lower panel-line, e, with a flattened curve, is formed between the points of its intersection with the knees C or their beams. The panel between the said lines d and e I make with an incline inward from top line e, or with a concave surface. The front of the back seat E is made with a straight inclined line, s, intersecting with the lines e and d, as shown. The front of the front seat G is made with a corresponding line at the same inclination, only in a reverse direction, while the sides of the said seat standing over the line a are made with a plain upper line, and the seat is provided with a straight back slightly inclined toward the dickey-seat. The runner B curves up in front with an easy sweep, and terminates at the lower side of the front of the body, and a little back of a base of the toe-board, so as to gracefully fall in with the lower line d of the body. The panelings may be either raised or sunken, and the several surfaces may be painted, striped, and ornamented, as taste and fancy might suggest.

This style of sleigh differs materially from the general prevailing styles, and presents so great a departure from the usual styles as to be very striking to the eye and pleasing to the beholder, on account of the new lines of the several parts being so diverse from the old lines heretofore used, and giving to the sleigh a general appearance of lightness and beauty, which conceals its strength and economy in construction.

This style of sleigh is adapted to receive any of the different styles of leather tops now in use with bodies of wheel vehicles, and can be variously trimmed or upholstered, as may be desired.

What I claim as my invention, in the design for a "Brett" sleigh, is—

1. In a sleigh, the conformation formed by the combination of the upper line a, commencing at the dickey-seat, with the lower line d, commencing at the bracket c of the toe-board, and terminating at x, and with the line a, as shown and described.

2. In a sleigh, the conformation formed by the combination of the curved line e with the lower line d, having an intervening panel between, substantially as shown and described.

3. In a sleigh, the conformation formed by the combination of the front line s of the back seat with the lines a and e, substantially as shown and described.

4. In a sleigh, the conformation formed by the combination of the front pillar-block line b with the toe-board F and the lower line d, substantially as shown and described.

5. In a sleigh, the conformation formed by the combination of the line d, toe-board F, and runner B, the said runner falling in with the line d on the lower side of the body at its front, and back of the base of the toe-board bracket c, as shown and described.

FRANCIS D. KENNEDY.
